JOHN P. BIRCH, OF PHILADELPHIA, PENNSYLVANIA, ASSIGNOR TO HIMSELF AND
GEORGE W. PATERSON, OF NEWBURYPORT, MASSACHUSETTS.

Letters Patent No. 66,671, dated July 16, 1867.

IMPROVEMENT IN ROTARY PUMPS.

The Schedule referred to in these Letters Patent and making part of the same.

TO WHOM IT MAY CONCERN:

Be it known that I, JOHN P. BIRCH, of Philadelphia, in the county of Philadelphia, and State of Pennsylvania, have invented certain new and useful improvements in Rotary Pumps; and I hereby declare the following to be a full, clear, and exact description of the same, reference being had to the accompanying drawings, in which—

Figure 1 represents a longitudinal vertical section, and

Figure 2 represents a transverse vertical section of a pump constructed in accordance with my invention.

Figures 3 and 4 represent a front and a side elevation of one of the pistons removed from the pump.

The pump in which my invention is illustrated is a rotary water-pump, in which the pistons or buckets, while placed within and moving in unison with the piston case or drum, nevertheless revolve eccentrically with respect to the said piston-case. Under this arrangement the pistons will not of course always maintain the same position in the case, which could only happen when the centres of motion of the two were identical and the same, but as they revolve they will be alternately and successively projected from and withdrawn within the case. The pistons and their drum are placed within a cylinder, where the former are mounted in one end of and concentrically with the interior of the cylinder, and the latter is mounted in the opposite end of and eccentrically to the same; and the location of the piston-case is such that the pistons or buckets, as they approach the nozzle or orifice from which the water is discharged, are gradually withdrawn within the case, thus allowing free passage for the water, and as they approach the induction side of the cylinder they are gradually thrust from the case into the water, which they conduct to the ejecting-nozzle.

To enable others skilled in the art to understand and use my invention, I will now proceed to describe the manner in which the same is or may be carried into effect by reference to the accompanying drawings.

The pistons and piston-case are contained within a cylinder, A, provided with two nozzles or pipes, the one, *a*, being the supply or induction, and the other, *b*, the ejection or discharge-nozzle. At the points where the nozzles connect with the cylinder, the interior of the cylinder is enlarged so as to form chambers into and from which the water may be readily drawn and discharged. The direction of the ejection pipe *b*, at the point where it leaves the cylinder, is that of a line tangent to the inner surface of the cylinder, so that the water is discharged by the pistons without any change of direction, and thus retains all the momentum which it has received from the pistons. This is a valuable feature of the pump, and one which peculiarly adapts it for use with a fire engine, where the greatest possible momentum is required. In one head of and eccentrically to the interior of the cylinder, the hollow piston-case B is mounted, through the sides and end of which a series of slots or passages is formed, equal in number to the pistons employed. The stem or shaft *c*, upon which the case is held, passes out through the head of the cylinder and carries a crank or handle, *d*, by means of which the case is rotated. The shaft *c* may also receive motion by means of any other suitable mechanism, from any motor, whether steam, water, or other power. The pistons whose revolution causes the water to flow from the discharge orifice *b*, consist each of a bucket or piston proper, *C*, and a disk or plate, *D*, the end of the bucket being attached to the periphery of the disk, and in such manner that the planes in which the two lie shall be transverse or at angles to one another. The pistons are placed together in pairs, and so that the buckets of each pair shall fit in the slots in the piston-case diametrically opposite each other. Thus the pistons *C C*, fig. 1, constitute one pair, and the pistons *C' C'* another pair. The interior opposite faces of the disks *D* of each pair are grooved and tongued concentrically, as shown in fig. 2, so as to admit of the movement of the pistons, and yet hold the disks together. This construction and arrangement of the pistons is productive of great advantages. The disks support and steady the buckets or pistons proper, while the concentric tongues and grooves, formed upon the contiguous faces of each pair, allow the pistons to adjust themselves readily to their constant change of position with relation to the piston-case. The pistons, although placed within and actuated by the piston-case, do not move concentrically therewith; on the contrary, they revolve around a rod or pin, *E*, attached immovably to the further head of the cylinder *A*, and at its centre, measuring from the two opposite concentric inner surfaces of the same. The pin, therefore, which extends into the piston-case, and consequently the pistons which it holds in position, are eccentric with respect to the piston-case, as shown clearly

in fig. 2. The pistons, at the points where they pass through the slots in the piston-case, are supported by packing-pieces *e* or "half rounds," which adjust themselves readily to the movement of the pistons and allow them free play.

The operation of the pump is as follows: When power is applied to the piston-rod *c*, the piston-case *B* is revolved in the direction of the arrows. This movement is imparted to the pistons *C*, which, as they approach the induction pipe *a*, are gradually thrust or projected from the piston-case, as shown in fig. 2. The pistons, when they occupy the position shown at *C' C'*, fig. 2, are in contact with the two opposite concentric surfaces of the cylinder, the one piston being entirely projected from and the other wholly withdrawn from the case. As they approach the discharge pipe *b* they are gradually drawn within the case, so as to give uninterrupted and free passage to the water, which is ejected in a continuous stream, none of the momentum of which is lost, owing to the position of the pipe or nozzle with relation to the interior surface of the cylinder.

When the pump is to be used in a place where it is required to be submerged, the piston-rod may be operated by connecting it to a shaft and crank located above the surface of the water, and actuated by steam or other power, as desired. The play of the pistons through the slots or openings in the piston-case is facilitated by the packing-pieces or "half rounds" which support them, and admit of their adapting themselves to various positions, and to project at different angles from the case. Owing to the construction of the pistons and the manner of uniting them together, each one can move independently of the other, in order to adjust itself to the varying form of the cylinder, and they all, while receiving motion, from the piston-case, revolve independently of and eccentrically to the same.

Having now described my invention, and the manner in which the same is or may be carried into effect, what I claim, and desire to secure by Letters Patent, is—

The combination, with the eccentric piston-case and central pin or spindle, mounted in opposite ends of the pump-case, of the pistons or buckets and their grooved and tongued supporting disks, mounted on said spindle, and within the piston-case, substantially as shown and described.

In testimony whereof I have signed my name to this specification before two subscribing witnesses.

JOHN P. BIRCH.
